UNITED STATES PATENT OFFICE.

JORAM PRIEST, OF DETROIT, MICHIGAN, ASSIGNOR TO APPLETON S. BRIDGES, OF ST. LOUIS, MISSOURI.

VEHICLE-SPRING.

SPECIFICATION forming part of Letters Patent No. 256,161, dated April 11, 1882.

Application filed December 23, 1881. (No model.)

To all whom it may concern:

Be it known that I, JORAM PRIEST, a citizen of the United States, residing at the city of Detroit, county of Wayne, State of Michigan, have invented a new and useful Improvement in Vehicle-Springs, of which the following is a specification.

Figure 1 represents a side elevation of my improved spring, and Fig. 2 a plan view of 10 the bottom of the same.

My invention relates to that class of springs used on side-bar vehicles; and my invention consists of a particular combination of a spring with the surrounding parts, all as will herein- 15 after be described in the specification, and pointed out in the claims.

In the drawings, letter B is a cross-piece fastened to the under part of the body in any ordinary way, or it may be mortised into the 20 side sills of the body, and thus become a part of it. To this the springs are attached at their respective ends, and upon the under side of it the springs rest and have a bearing at the crown or apex of the center curve.

25 A A are two double-acting springs, made of one or more leaves curved downward in a gentle curve at or near their respective centers and curved upward at each of their respective ends. This latter curving, however, is not absolutely 30 necessary to the complete working and utility of my spring. The springs are then connected at one end to the under part of the cross-bar B, and the apex of the center curve is allowed to rest upon the under side of said cross-bar 35 B, where they may or may not be attached in any ordinary way. In the drawings they are represented as attached by a common T-shaped clamp, J, passing up through the cross-bar B. The respective corresponding ends of the 40 springs are attached to the cross-bar B by toggles f f, but may be attached in any ordinary manner.

d d are the sectional views of the side bars of the vehicle, to which springs are attached. 45 By this construction of the springs I secure the double action of the spring. Thus when the spring is bent up at the side bars, d d, it has a tendency to press downward at the point f. This gives a downward action to the spring 50 from the apex of the center curve to the point

where it is attached to the cross-bar at f, and an upward motion from the apex or crown of the spring to the point d, where it is attached to the side bar. This movement, which is different from every other cross-bar spring, secures me the entire length of spring from the point to which it is attached to the cross-bar B to the point to which it is attached to the side bar, d, and when the two are combined as shown in the drawings—that is, put side by side and crossing over, as shown in the drawings—it gives the spring motion from side bar to side bar, thus securing all the elasticity of a long spring, with all the strength of several short springs; but the manner of constructing the 65 springs and attaching them to the body and side bars, so as to get a double-acting semi-elliptic spring, and at the same time lower the body down as in other side-bar springs, is what I claim as the patentable feature of my invention. This can be secured whether I run my springs lengthwise, crosswise, or diagonally across the body.

I am aware that it is old to provide the body of a vehicle with springs attached to the bottom thereof equidistant from the side and projecting in opposite direction, and having one of the curves of each spring attached at or near the point where the end of its mate is attached; but this form differs from mine in 75 that it requires a plate having lugs, which are liable to snap from a sudden jolt, and several bolts to hold the parts together. One of the bolts is also inserted through the body of the spring, which is thereby weakened, whereas 80 in mine the springs are made to lap by means of a curve at or near the center, and are held in place by a T-bolt, thus dispensing with the holes and forming a strong elastic support for the body. The weight is also more evenly distributed upon the springs, thus preventing the 85 jolting and tilting that a body which is only supported at the sides is subject to.

I am also aware that it is not new to provide vehicles with springs attached to the 95 body by means of adjustable fulerums or rests, whereby the elasticity of the springs may be adjusted to suit different loads. This device differs from mine in that a rod must be attached to the bottom for the fulerums to slide 100

upon, whereas I loosely attach the curved parts of the springs to the bottom of the body by means of a T-bolt, which, while holding both springs in place, allows them to automatically adjust themselves to suit loads of different weights.

What I claim as new is—

1. In a vehicle, two springs arranged parallel to each other and projecting in opposite directions, in combination with the body, having a T-bolt, which holds both springs against the body, and at the same time allows them to automatically adjust themselves, for the purpose set forth.

2. In a vehicle, the combination, with the body and frame, of curved springs arranged in pairs, projecting in opposite directions, and having their respective ends attached to the body and frame and their curve loosely attached to the center of the bottom of the body, forming a movable fulcrum, which automatically adjusts itself to the variant conditions of the body.

JORAM PRIEST.
